UNITED STATES PATENT OFFICE.

JOSEPH GEORGE TURNBULL, OF NEW YORK, N. Y.

DESIGN FOR A BRACKET.

42,382.

Specification for Design.

Patented Apr. 2, 1912.

Application filed January 12, 1912. Serial No. 670,948. Term of patent 7 years.

To all whom it may concern:

Be it known that I, JOSEPH GEORGE TURNBULL, a citizen of the United States, residing at New York, in the county of New York and State of New York, have invented a new, original, and ornamental Design for Brackets, of which the following is a specification, reference being had to the accompanying drawing, forming a part thereof,

in which the figure is a perspective view of the bracket.

I claim:

The ornamental design for a bracket, as shown.

JOSEPH GEORGE TURNBULL.

Witnesses:

MAYME A. TURNBULL,
MARGARIE C. HARDING.

Copies of this patent may be obtained for five cents each, by addressing the "Commissioner of Patents, Washington, D. C."
